(57) **CLAIM**

The ornamental design for a cylindrical load collar for a delineator system, as shown and described.

DESCRIPTION

FIG. 1 is a front, top perspective view of a cylindrical load collar for a delineator system of our design.

FIG. 2 is a front, elevation view of a cylindrical load collar for a delineator system of our design.

FIG. 3 is a rear elevation view of a cylindrical load collar for a delineator system of our design.

FIG. 4 is a left side, elevation view of a cylindrical load collar for a delineator system of our design.

FIG. 5 is a right side, elevation view of a cylindrical load collar for a delineator system of our design.

FIG. 6 is a top plan view of a cylindrical load collar for a delineator system of our design.

FIG. 7 is a bottom plan view of a cylindrical load collar for a delineator system of our design.

FIG. 8 is a cross section view of a cylindrical load collar for a delineator system of our design taken along line 8-8 of FIG. 6.

FIG. 9 is a front, top perspective view of a cylindrical load collar for a delineator system; and,

FIG. 10 is a front, top perspective view of a cylindrical load collar for a delineator system.

The broken lines shown in FIGS. 9-10 depict unclaimed environmental subject matter.

1 Claim, 7 Drawing Sheets
